UNITED STATES PATENT OFFICE.

GEORGE HAKE, OF ST. LOUIS, MISSOURI.

GARMENT-SUPPORTER.

1,337,131.

Specification of Letters Patent.

Patented Apr. 13, 1920.

Application filed June 9, 1919. Serial No. 302,873.

To all whom it may concern:

Be it known that I, GEORGE HAKE, a citizen of the United States of America, a resident of the city of St. Louis, State of Missouri, have invented certain new and useful Improvements in Garment-Supporters, of which the following is a full, clear, and exact description, reference being had to the accompanying drawings, forming a part of 10 this specification.

My invention relates to a garment supporter, and more particularly to an improvement on the standard type of garment attaching devices now in general use, the object being to provide a strong and simple fastening device whereby the garment is firmly secured without materially wrinkling the garment at the fastening elements.

The device herein disclosed comprises a garment receiving loop having side members and a bottom member, the side members being separated from each other to receive the garment holding button, and the bottom member being in the form of a bow providing a spreader on which free portions of the garment are permitted to spread away from the button. The button co-operates with the side members of the loop to secure the garment, and when the device is in service, the garment is firmly pulled onto the bow which serves as a spreader for portions of the garment at opposite sides of the button, thereby eliminating wrinkles which ordinarily occur at the portions of the garment adjacent to the button.

Figure I is a front elevation illustrating a garment supporter secured to a portion of a garment.

Fig. II is a vertical section of the device shown in Fig. I, the garment being omitted.

Fig. III is a front elevation of the device with the garment omitted.

Fig. IV is an enlarged detail view showing the lower portion of the garment receiving loop.

The garment supporter herein shown comprises a suspension member 1, preferably an elastic strap, and wire loop 2 through which the suspension member passes, and a garment receiving loop A below the loop 2. In Fig. I I have shown a portion of the garment G secured by the loop A and a button B.

The garment receiving loop A is provided with a horizontal top member 3 located adjacent to the loop 2 and pivotally secured

thereto by means of a flattened tube 4 which surrounds the adjacent members of the loops 2 and A.

The button B has a head 5 and a neck 6 secured to a flexible suspension strap 7 which passes around the tube 4. The flexible strap 7 serves as means for attaching the button to the top of the garment receiving loop. The button is preferably made of 65 rubber or other yielding material.

The garment receiving loop A may be a single piece of wire bent to form an upper loop member 8 through which the strap 7 is inserted, and an intermediate loop or opening adapted to receive the head of the button. The side members of the garment receiving loop are bowed away from each other, as shown at 9, to form the large loop or opening through which the button is inserted, and these side members have approximately vertical lower portions 10 which are separated from each other to receive the neck of the button. These lower portions 10 have diverging lower ends 11.

The bottom member 12 of the garment receiving loop is preferably in the form of a bow which extends downwardly at opposite sides of the button to provide a spreader on which free portions of the garment G are 85 permitted to spread away from the button and toward the lower ends of the bow. The diverging members 11 are connected to the bow by means of return bends 13. The bow 12 is separated from the diverging members 11 to provide oppositely disposed garment receiving recesses over the lower ends of the bow, and these recesses are located at opposite sides of the neck of the button to receive free portions of the garment.

In securing the garment G, the button together with a portion of the garment is inserted between the bowed portions 9 of the side members and then forced downwardly to the position shown in Fig. I. The neck 100 6 of the button passes downwardly between the side members 10, and the head 5, covered by the garment, lies in front of the side members. When the button is thus forced to the position shown in the drawing the neck 105 6 lies between the side members 10 at a point immediately above the middle of the bow 12, so as to firmly engage the garment between said neck and the separated side members and also between the neck and the relatively high middle portion of the bow. It will be noted that the garment is thus firmly

secured or clamped at only three points which are indicated by X in Fig. I, one of said points being at the bottom of the neck where the neck lies very close to the middle 5 portion only of the bow 12, and the other points being at opposite sides of the neck where it coöperates with the side members 10. The garment is not tightly held or clamped in the recess 15 at opposite sides 10 of the neck 6. These open recesses 15 are smaller than the neck of the button so as to prevent said neck from entering the recesses.

The head 5 of the button lies in front of 15 the middle portion of the bow 12 and also in front of the side members 10; however, the head 5 preferably does not completely cover the open recesses 15.

By combining the several elements with 20 each other in the manner herein disclosed, the button will properly coöperate with the loop to firmly secure the garment, and undesirable wrinkling of the garment will be almost entirely eliminated at the lower 25 end of the loop. The button neck 6 will coöperate with the bow 12 and side members 10 to firmly hold the garment at three separated points leaving adjacent portions of the garment free to be pulled into the open recesses 15 at opposite sides of the neck. When the device is in service, the garment 30 will be firmly pulled onto the bow 12 which serves as a spreader for the free portions of the garment at opposite sides of the neck, 35 causing said free portions to spread away from the neck and pass into the open recesses 15 thereby eliminating wrinkles which ordinarily occur at the neck of the button. If the device did not have the recesses 15 nor 40 the spreader bow 12, portions of the garment would be crowded around the neck of the button with the result of causing numerous folds or wrinkles at the rear of the fastening elements.

45 The new combination of elements eliminates the undesirable wrinkling and at the same time secures the garment more effectively than the ordinary fastener now in general use, for the portions of the garment 50 spread out on the bow 12 will be exposed to the long holding surface of the bow and this long surface is well adapted to coöperate with the head and neck of the button to firmly secure the garment, without liability of tearing or mutilating the same.

I claim:

1. A garment supporter having a garment receiving loop provided with side members separated from each other to receive a portion 60 of the garment and a bottom member connecting the separated side members, a button extending through said loop and coöperating with said side members and bottom member to secure the garment, said 65 bottom member being in the form of a bow

extending downwardly at opposite sides of the button to provide a spreader on which portions of the garment at opposite sides of the button are permitted to spread toward the ends of the bow, the lower portion of 70 said garment receiving loop being provided with oppositely disposed garment receiving recesses over the ends of said bow, said button having a head which lies in front of said side members and a neck which lies 75 between and coöperates with said side members at a point above said recesses and also above the middle of said bow.

2. A garment supporter having a garment receiving loop provided with side members 80 separated from each other to receive a button with a portion of the garment, said separated side members having diverging lower ends, a bottom loop member connecting said diverging lower ends, a button extending through said loop and coöperating with said side members and bottom member to secure the garment, said bottom member being in the form of a bow extending 85 downwardly at opposite sides of the button to provide a spreader on which free portions of the garment are permitted to spread away from the button and toward the ends of the bow, the lower portion of said garment receiving loop being provided with oppositely 90 disposed open garment receiving recesses over the ends of said bow and said recesses being located at opposite sides of the button to receive said free portions of the garment. said button having a head which lies in front 95 of said separated side members and a neck which lies between and coöperates with said side members at a point immediately above said recesses and also above the middle of said bow, so as to firmly engage the garment 100 between said neck and the separated side members and also between the bottom of the neck and the relatively high middle portion of said bow, and said open garment receiving recesses being narrower than the neck of 110 the button so as to prevent said neck from entering the open recesses.

3. A garment supporter comprising a button having a head and a neck, and a garment receiving loop comprising side members 115 widely separated from each other to receive the head of the button with a portion of the garment, said side members having lower portions separated from each other to closely fit the neck of the button, and said 120 side members having diverging lower ends extending away from the neck of the button. an elongated bottom member connecting said diverging lower ends to form a spreader for portions of the garment at opposite sides of 125 said neck, said spreader being separated from said diverging lower ends to provide open garment receiving recesses at opposite sides of said neck and said recesses being adapted to communicate with the space be- 130

tween said side members so as to receive portions of the garment forced there-through, said open recesses being narrower than the neck of the button so as to prevent
5 said neck from entering the open recesses, the bottom face of said neck being adjacent to the middle portion only of said spreader and opposite sides of said neck being adjacent to said side members at points above
10 said open recesses so as to securely hold the

garment at points above the recesses, leaving portions of the garment free to spread away from said neck and into the open recesses between said spreader and said diverging lower ends, and the head of said button 15 being in front of said side members and spreader.

In testimony that I claim the foregoing I hereunto affix my signature.

GEORGE HAKE.
